TAKE-UP MECHANISM FOR LOOMS

Application filed September 11, 1930. Serial No. 481,121.

This invention relates to novel mechanism for rotating the spike or take-up roll of a loom either by manually operated means or from a going part of the loom, and to simple means for placing the take-up roll under the control of either form of driving mechanism.

It is now the ordinary practice to provide looms with take-up mechanism for driving the spike or take-up roll from a going part of the loom so that the fabric will be drawn forward at the proper speed as woven, and it is desirable to so construct the take-up mechanism that the take-up roll may be readily turned back when a mis-pick or other defect occurs in the fabric.

An important feature of the present invention therefore resides in improvised mechanism whereby the spike or take-up roll is normally driven from a going part of the loom but may be easily released therefrom for manual rotation, and then readily placed again under the control of the power operating mechanism with the proper tension on the fabric.

Since the take-up mechanism is relied upon to a large degree to control the placing of the proper number of picks in the fabric per inch, it is important that care be taken each time the take-up roll is released from the power driving mechanism, to see that the proper tension is placed upon the fabric when the take-up roll is again placed under the control of the power drive.

It is therefore important that the manually shiftable means for placing the take-up roll under the control of either the power driving mechanism or the manually operable means, be so constructed that the parts can be readily engaged to automatically operate the take-up roll after the latter has been turned to a position to place the desired tension upon the fabric.

This is accomplished in accordance with the present invention by providing the power driving connections for the take-up roll with cooperating gear means that are so constructed that the teeth of the cooperating parts may be readily moved into and out of locking engagement with each other irre-

spective of the angular rotation of one relative to the other. More specifically, an important feature of the present invention resides in clutch means between the power drive and take-up roll comprising an internal gear having associated therewith a gear, the teeth of which are adapted to be moved into and out of locking engagement with the teeth of the internal gear.

Other features of the invention and novel combination of parts, in addition to the above, will be hereinafter described in connection with the accompanying drawings which illustrate one good practical form of the invention.

In the drawings:—

Fig. 1 is a front elevation of the left-hand side of a loom provided with the take-up mechanism of the present invention;

Fig. 2 is a sectional view taken on the line 2—2 of Fig. 1; and

Fig. 3 is a sectional view through locking gears to be described.

While the take-up mechanism of the present invention may be employed upon various types of looms, it is designed more particularly for use upon looms weaving a relatively heavy fabric such as carpets or the like where a strong tension is maintained upon the warp threads, making it necessary to impart a strong rotative force to the spike or take-up roll. The features of the present invention have, therefore, been illustrated in connection with a loom designed more particularly for weaving a pile fabric such as carpet, and the fabric shown in the drawings is therefore illustrated as a pile fabric. It will be understood, however, that it is immaterial so far as the present invention is concerned whether the fabric being woven is plain or otherwise constructed so long as it requires a relatively strong driving mechanism to operate the spike or take-up roll.

In the construction shown the loom parts, 95 are supported by the usual side frames 1, which are secured in spaced relation to each other by the longitudinally extending beam 2. These side frames, only one of which is illustrated in the drawings, may have any

preferred construction to support the operating parts of the loom to be described.

The loom shown is provided with the usual lay 3, which is supported by the lay 5 swords 4 and rocking shaft 5 for rocking movement towards and from the front of the loom in a well known manner under the action of the pitman arms 6. The lay 3 is shown as provided with the reed 7 10 of the usual construction, which is supported at its upper end by the reed cap 8 carried by the upper portion of the lay swords, and the shuttle box 9 is provided with a binder 10 having associated therewith the 15 binder finger 11 and dagger 12, as usual.

At each end of the lay is provided a picker stick 13 of the usual or any preferred construction and the means shown for operating a picker stick comprises a 20 picker shaft 14 which is journaled near its lower end in the supporting bracket 15 and to the shaft 14 is secured the curved picker shoe 16, the outer end of which is operatively connected to the picker stick by the 25 strap 17.

In the construction shown the fabric F produced from the warp strands W is advanced from the lay over the breast beam 18 and around the spike roll or take-up 30 roll 19, which is rotatably supported at its opposite ends by the bearings 20 carried by the side frames 1, and these bearings are so positioned that the upper surface of the roll lies in the horizontal plane of the 35 upper face of the breast beam. The fabric F passes around the spike or take-up roll 19, as shown, and then downwardly to the cloth roll 21, which is provided at its opposite ends with the stub shafts 22 journaled 40 in the bearing brackets 23 having the removable cover plates shown.

The mechanism so far described forms no essential part of the present invention, but has been illustrated and briefly described 45 to make clear the construction and operation of the take-up mechanism of the present invention now to be described.

In the embodiment of the invention shown the central shaft 24 of the spike or take-up roll 19 is provided at its left hand end in Fig. 1 with a worm wheel 25 adapted to be driven by the worm 26. This worm is rotatably mounted on a shaft 27, and the worm and shaft are rotatably supported 55 by the bearing bracket or casing 28, which preferably constitutes a housing for the worm 26 and the worm wheel 25, as shown.

The shaft 27 in the construction shown has positively secured to its inner end a 60 driving gear 29 adapted to be driven by the change gear 30 removably secured to the change gear shaft 31, and this change gear is rotatably supported in the bearing bracket 32 which is adjustably secured to 65 the frame 1 by the bolts 33. The arrange-

ment is such that the speed at which the spike or take-up roll 19 is driven from a rotating portion of the loom, to be described, may be varied as desired by varying the size of the change gear 30 which is keyed 70 to the shaft 31 and retained in place thereupon by any suitable means such as the removable screw 34 and washer 35.

In the construction shown the change gear shaft 31 is driven by the drive shaft 75 36 provided at its opposite ends with the universal joints 37, and the shaft 36 is provided at one end with the sliding sleeve connection 38. The shaft 36 is conveniently driven from the bottom shaft 39 provided 80 with the worm 40 adapted to drive the worm wheel 41, connected to the drive shaft 36.

As hereinbefore stated, it is important to provide means whereby the spike or take-up roll may be rotated manually as well as 85 automatically and the mechanism for conveniently placing this roll under the control of either power or manually operated means will now be described.

In the embodiment of the invention shown 90 the worm 26 is provided at its opposite ends with reduced tubular portions that are journaled in the supporting bracket 28 and the tubular portion at the outer end of the worm 26 is provided with an outwardly extending annular flange 42. To this flange 42 is rigidly secured a ring gear 43 which is provided with external and internal teeth. The driving worm shaft 27 is provided with a projecting end portion having keyed thereto for sliding movement the sliding gear 44.

The hub of this gear is provided with the nob 45 adapted to be engaged with the fingers to shift the gear 44 longitudinally of the 105 shaft 27 to move its teeth into and out of locking engagement with the ring gear 43.

It will be seen from the construction of the take-up mechanism so far described that the driving shaft 27 is continuously driven 110 during the operation of the loom from the bottom shaft 39 through the driving connections above described and it, therefore, follows that if the sliding gear 44 is moved into locking engagement with the teeth of the ring gear 43, as shown in Fig. 2, the worm 26 will be positively driven from the shaft 27 to rotate the spike or take-up roll. If, however, the nob 45 of the sliding gear 115 44 is engaged by the fingers and this gear is moved outwardly upon the shaft 27 sufficiently to disengage its teeth from the teeth of the ring gear 43, the take-up roll 19 will be released from the power driven shaft 27 and may be manually rotated independently 120 thereof.

The manual rotation of the spike or take-up roll 19 is secured in the embodiment of the invention illustrated by providing the hand actuated pinion 46 which is connected to a 125

stub shaft 47 so that its teeth mesh continuously with the external teeth of the ring gear 43 and the shaft 47 is provided at its outer end with a squared portion 48 adapted to receive a crank handle or the like (not shown) for manually rotating the gears 46 and 43 to thereby rotate the worm 26 and spike or take-up roll 19.

It is important to note that since the sliding gear 44 and ring gear 43 constitutes the manually shiftable driving connections between the shaft 27 and worm 26, the manually operable stub shaft 47 is at all times positively connected to the take-up roll for manual operation of the latter as soon as the sliding gear 44 is moved out of engagement with the ring gear 43, and since these two gears are provided with a number of cooperating teeth the teeth may be moved into locking engagement with each other when one has been rotated relative to the other through one or more small increments of a complete revolution, to thereby facilitate the placing of the take-up roll 19 under the control of the driving shaft 27 as soon as the take-up roll has been rotated by hand sufficiently to place the desired tension upon the fabric F.

As above stated, the fabric F passes downwardly from the spike or take-up roll 19 to the cloth roll 21 and the roll 21 is rotated in the construction shown by the ratchet wheel 49 and cooperating dog 50. This dog is mounted upon the cloth roll operating lever 51, which lever is pivotally mounted upon the frame 1 at 52. The lever 51 is shown as having a forked rear end portion 53 which is adapted to cooperate with the stud 54 projecting laterally from the lay sword 4. The arrangement is such that a spring 55 connected to the lever 51 tends to pull the same downwardly in a direction to cause the pawl 50 to rotate the ratchet wheel 49 in the direction indicated by the arrow in Fig. 2. Each time the lay beats up the stud 54 will engage the upper curved prong 53 to lift the same, if the tension of the spring 55 has been sufficient to pull the lever 51 down in the cloth roll rotating direction. The means just described for rotating the cloth roll 21 constitutes a simple construction controlled by the tension of the fabric for automatically rotating the cloth roll 21 at the proper speed, and the cloth roll is prevented from rotating in the cloth unwinding direction by the fixed dog 56.

The worm wheel 25, worm 26 and gears at the opposite ends of the shaft 27 are preferably enclosed in the housing 28 having the upper removable portion 47, but the opening in this casing about the shaft 27 is sufficiently large to permit the sliding gear 44 to be readily shifted into and out of locking engagement with the ring gear 43. The sliding movement imparted to the gear 44 is

preferably limited by the screw 58 projecting from the hub of this gear into a limit slot 59 formed in the shaft 27.

It is desirable to provide means for frictionally holding the sliding gear 44 in the position to which it is manually adjusted, and this is readily accomplished by providing the shaft 27 with the spring actuated ball 60 adapted to enter either one of the notches 61 in the hub of the gear 44.

What is claimed is:—

1. In a take-up mechanism for looms, the combination of a take-up roll, a worm and worm gear for rotating said roll, a power operated shaft for driving the worm to rotate the roll from a going part of the loom, a ring gear connected to said worm and provided with internal and external teeth, manually operable means engageable with said external teeth to rotate the ring gear and worm, and adjustable means movable into engagement with said internal teeth to drive the ring gear and worm from said shaft and movable out of engagement with the internal teeth to release the ring gear and worm from the shaft.

2. In a take-up mechanism for looms, the combination of a take-up roll, a worm and worm gear for rotating said roll, a power operated shaft for driving the worm to rotate the roll from a going part of the loom, a ring gear connected to said worm and provided with internal and external teeth, manually operable means engageable with said external teeth to rotate the ring gear and worm, and a gear slidably secured to said shaft and adapted to be moved into engagement with said internal teeth to lock the shaft and worm together and movable out of engagement with the internal teeth to release the ring gear and worm from the shaft.

3. In a take-up mechanism for looms, the combination of a take-up roll, a worm and worm gear for rotating said roll, a power operated shaft for driving the worm to rotate the roll from a going part of the loom, a ring gear secured to said worm and provided with internal and external teeth, a gear slidably mounted upon said shaft and movable into engagement with said internal teeth to drive the worm from said shaft and movable out of engagement with said teeth to release the ring gear from said shaft, means for manually rotating said ring gear to turn the roll, and a casing enclosing the worm, worm gear and sliding gear.

4. In a take-up mechanism for looms, the combination of a take-up roll, gear mechanism for rotating said roll, a power operated shaft for driving said gear mechanism to rotate the roll from a going part of the loom, manually operable means for rotating said gear mechanism independently of said power shaft, and clutch means for placing

- the take-up roll under the control of either said shaft or said manually operable means, including an internal gear and an external gear adapted to be shifted into and out of locking engagement with each other, and constructed so that one may be shifted into locking engagement with the other when turned relative thereto through one or more small increments of a complete circle.
5. In a take-up mechanism for looms, the combination of a take-up roll having a worm gear, a shaft having a worm loosely mounted thereon and engaged with the worm gear, power means for driving said shaft, a ring gear secured to the worm and having internal and external teeth, a gear splined to said shaft and movable longitudinally thereof into and out of engagement with the internal teeth of the ring gear, and a manually operable gear continuously engaged with the external teeth of the ring gear for turning the take-up roll manually when the gear splined to the said shaft is disengaged from the internal teeth of the ring gear.
6. In a take-up mechanism for looms, the combination of a take-up roll having a worm gear, a worm supporting shaft having a worm loosely mounted thereon and provided with a ring gear secured thereto, a gear secured on the worm supporting shaft for rotative movement therewith and longitudinal movement thereon into and out of engagement with the ring gear, a manually operable gear in continuous engagement with the ring gear for turning the latter manually when the ring gear is disengaged from driving connection with the worm supporting shaft.
7. In a take-up mechanism for looms, the combination of a take-up roll having a worm gear, a worm supporting shaft having a worm loosely mounted thereon, a power transmitting gear secured to one end of the worm supporting shaft, a power shaft having a change gear engaged with the power transmitting gear, a gear secured to the worm and having two sets of teeth, a gear splined to the worm supporting shaft and movable longitudinally thereof into engagement with one of said sets of teeth to operate the take-up roll by power and at a speed dependent upon the change gear, a manually operable gear in continuous engagement with the other set of teeth of the gear secured to the worm that the take-up roll may be manually turned at a uniform speed when the splined gear is moved longitudinally of the worm supporting shaft out of engagement with the worm gear.
8. In a take-up mechanism for looms, the combination of a take-up roll, a worm supporting shaft, a worm and worm gear for rotating the take-up roll, a power shaft for rotating the worm, a gear having two sets of teeth and secured to the worm, a

manually operable gear in continuous engagement with one of the sets of teeth to rotate the take-up roll, and a gear splined to the worm supporting shaft and movable longitudinally thereof into engagement with the other set of teeth to cause power operation of the take-up roll and movable longitudinally of the worm supporting shaft in the opposite direction to free the worm to actuation by the manually operable gear.

In testimony whereof, I have signed my name to this specification.

EDWIN W. STONE.
